CLAIM

The ornamental design for a stackable coupler for electrical cables, as shown and described.

DESCRIPTION

FIG. 1 is a perspective view of a stackable coupler for electrical cables according to the present invention.

FIG. 2 is a rear view of a stackable coupler for electrical cables shown in FIG. 1.

FIG. 3 is a side view of a stackable coupler for electrical cables shown in FIG. 1.

FIG. 4 is a bottom view of a stackable coupler for electrical cables shown in FIG. 1.

FIG. 5 is a top view of a stackable coupler for electrical cables shown in FIG. 1.

FIG. 6 is a front view of a stackable coupler for electrical cables shown in FIG. 1.

The broken lines are for illustrative purposes only and form no part of the claimed design.
